their Attorney

UNITED STATES PATENT OFFICE.

VICTOR GLADSTONE STEER, OF KILLARA, NEAR SYDNEY, AND FRANK MCLENNAN LENNARD, OF DARLINGHURST, SYDNEY, NEW SOUTH WALES, AUSTRALIA.

ELECTRICALLY-HEATED CUSHION AND THE LIKE.

Application filed October 8, 1923. Serial No. 667,107.

To all whom it may concern:

Be it known that VICTOR GLADSTONE STEER and FRANK MCLENNAN LENNARD, subjects of the King of Great Britain and Ireland, residing, respectively, at Stanhope Road, Killara, near Sydney, New South Wales, Commonwealth of Australia, and 121 Victoria Street, Darlinghurst, Sydney aforesaid, have invented certain new and useful 10 Improvements in Electrically-Heated Cushions and the like, of which the following is a specification.

This invention relates to cushions, quilts, counterpanes, pillows, eiderdowns, and like 15 articles which have associated with them an electric heating element adapted to be connected to a current source of supply.

One embodiment of the invention is illustrated in the accompanying drawing in 20 which Fig. 1 is a perspective view of a heating element frame having electric lead wires attached thereto; Fig. 2 a detail sectional view of such element with an outer cover thereon; Fig. 3 a cross-section; Fig. 4 25 a view illustrating details of the heating element; Fig. 5 detail views of parts of the heating element; and Fig. 6 a perspective view of a connector.

Referring to the accompanying drawings, 30 a frame of felt 1 or other suitable material is provided; this frame is constructed with a series of open-ended pockets 2 arranged side by side. The said pockets 2 may be formed by stitching the felt 1 or other material at suitable positions, say by lines of 35 stitches 3.

When said pockets 2 have been formed they have threaded therein an electric heating element 4 which consists of a base of asbestos or like cord 6 with which is associated an electric conductive wire 7 of high resistance, a protective cord of asbestos 8 or the like being wound on the resistance wire 7 and the base cord 6. Said heating 45 element 4 is first threaded into the first of the said pockets 2 leaving one free end of the said element protruding therefrom; the said element 4 is then threaded successively through each of the other pockets 2 and is 50 returned through said latter pockets, so that eventually the opposite free end of the element 4 is allowed to protrude from the first of said pockets. A continuous length of element 4 is thus carried by the said frame 1 with the opposite free ends of the said ele-

ment projecting from one end of the said frame; preferably there is a piece of felt 5 or the like situated between the overlying layers of the element 4 in the pockets 2, and an opening 9 is provided in said piece of 60 felt 5 to enable the element 4 to be passed therethrough to permit its return through the series of pockets 2 to the first pocket.

Insulated lead wires 10 from any convenient source of electric current supply are connected to the resistance wire 7 of the heating element 4 by baring the connecting ends of 65 said wires 10 and attaching them respectively to the opposite ends of the high resistance wire 7 of the element 4. It is preferable to twist the opposite ends of the high 70 resistance wire 7 around the ends of the lead wires 10 and then to weld both wires 7 and 10 to each other; this may be conveniently achieved by separating the bared ends of the 75 lead wires 10, coiling the end of the high resistance wire around one of said separated ends, then coiling the other separated end of the lead wire 10 around the already coiled joint of the high resistance wire 7 and one 80 separated end of the lead wires 10, and finally welding the coiled joints of wires 7 and 10 to each other (see Fig. 5).

A metal connector 11 preferably of 85 U-shape and consisting of copper is utilized for the purpose of securing the opposite ends of the element 4 to the insulated lead wires 10. The said connector 11 is placed about the opposite ends of the element 4, and after the jointed ends of the lead wires 10 and the 90 resistance wire 7 have been placed therein, and part of the asbestos cord 8 or the like of the element 4 has preferably been tucked over the joint connection between the said lead wires 10 and the said resistance wire 7 95 of the element 4, said U-connector is clamped about the joined ends of the element 4 and the lead wires 10 to make a secure joint.

For the purpose of enclosing the said felt or like frame 1 and the felt piece 5 a casing 12 of felt or other suitable material is provided; one end of said casing is left open in manufacture. Before the frame 1 has been inserted within said casing 12 the opposite ends of the element 4 are secured to said frame 1 by stitching 13 or otherwise, preferably by stitching at points on opposite sides of the element 4 at which the U-connectors 11 are situated. The lead wires 10 are then 105 suitably twisted or knotted to each other as 110

at 14, and the knot or the like is inserted within the said casing 12, whereupon the open end of the said casing is closed by stitching or otherwise with the said knot or 5 the like on the interior of the casing. It is preferred to construct the frame 1 and felt 5 of sufficient length and width whereby a clear space will be left at the edges to enable the frame 1, and felt 5 to be finally se- 10 cured to each other by stitching 15. The fastening of the element 4 to the frame 1 after the U-connectors have been clamped to the said element and lead wires 10, and the subsequent closing of the open end of the cas- 15 sing 12 with the knot or the like 14 on the lead wires 10 within the casing 12 ensure a secure joint connection for the lead wires 10 and the resistance wire 7 of the element 4.

The frame 1 with the element 4 therein 20 and the casing 12 therefor may be enclosed within a flannel or any other suitable outer cover 16 whereby a cushion, pillow, quilt, or other like article may be provided adapted to be heated electrically when current is 25 supplied to the high resistance wire 7 of the element 4.

What we claim as our invention and desire to secure by Letters Patent is:—

1. In an electric heating pad of the character described, the combination of outer 30 flexible sheets, an intermediate sheet having a communicating opening therethrough, and a heating element comprising a continuous strand of wire bent to form loops and having one of said loops disposed at right angles 35 to the others and projecting through said opening in the intermediate sheet.

2. An electric heating pad, as claimed in claim 1 in which said intermediate and outer sheets are stitched together along parallel 40 lines intermediate said loops, whereby pockets are formed to enclose parallel portions of said heating element.

In testimony whereof we affix our signatures in presence of two witnesses.

VICTOR GLADSTONE STEER.
FRANK McLENNAN LENNARD.
